(57) CLAIM

I claim the ornamental design for the salon dryer chair, as shown and described.

DESCRIPTION

FIG. 1: is the front right perspective elevation view of the salon dryer chair;

FIG. 2: is the left elevation view thereof;

FIG. 3: is the front elevation view thereof; and,

FIG. 4: is the right elevation view thereof.

The broken line portion of the figure drawings is included to show portions of the article that forms no part of the claimed design.

1 Claim, 4 Drawing Sheets
